UNITED STATES PATENT OFFICE.

DAVID ELLIS HAMBURGER, OF MOUNT VERNON, NEW YORK.

ILLUSIONARY BOX.

Application filed October 13, 1919, Serial No. 330,368. Renewed March 2, 1922. Serial No. 540,570.

To all whom it may concern:

Be it known that I, DAVID ELLIS HAMBURGER, a citizen of the U. S. A., residing at Mount Vernon, N. Y., have invented new 5 and useful Improvements in Illusionary Boxes, of which the following is a specification.

This invention relates to illusionary devices which create the impression in the 10 viewer's mind that he sees something that he does not in reality. The invention is for application particularly to boxes or containers for small articles that are customarily laid open to view when on sale, such as candy, 15 pens, pencils, cigars, etc., and the object of the invention is not to mislead prospective purchasers but to present a true picture of the contents of a box so that they think they are seeing the real articles within the box. 20 In this way, perishable articles, or articles sensitive to temperature or moisture changes can be thoroughly preserved within their containers without in any way detracting from the purchaser's knowledge of what the 25 boxes contain.

The invention, then consists of a box or container whose peripheral lines (in plan view) follow the laws of either a true or isometric perspective and upon which box 30 is applied a picture of a box in perspective having a transparent top through which can be clearly seen the contents of the box. In other words, if a person looks directly down upon my improved box, he sees the picture 35 carried by the top of the box which makes him think that he sees the box in perspective, that it has a transparent top, and that he sees the contents thereof.

The invention is illustrated in the accompanying drawings in which—

Figure 1 is a plan view of one form of box made in accordance with this invention but without any picture applied to its top.

Fig. 2 shows a side elevation of the box.

Fig. 3 shows one type of the label, print, or picture applied to the top of the box.

Fig. 4 shows in perspective, the box with the picture carried by its top.

Fig. 5 shows a plurality of boxes made in accordance with this invention to illustrate the appearance of a group of them.

Fig. 6 shows a round appearing box (instead of the rectangular appearing one of the preceding figures) made in accordance 55 with this invention, and

Fig. 7 shows a hexagonal appearing box.

In the drawings, the numeral 11 represents the top of a rectangular appearing box, 12 and 13 parallel sides; 14 and 15 parallel sides and 16 and 17, two substantially parallel sides or faces formed by cutting off two diagonal corners of the box. The sides or faces 16 and 17 are inclined away from the vertical and are either parallel or slightly converging with respect to 60 each other to fulfil the laws of either true or isometric perspective.

18 represents the label, print or picture which is to be applied to the top 11 of the box. This picture may be applied in any 70 way to the top of the box, produced by any process, and in black and white or colors or any combination thereof. The box may be of any material. It will be noticed that the periphery or shape of the label corresponds to or is identical with the top of the 75 box.

This picture 18 preferably shows in perspective, a box having a transparent top through which can be seen the contents of 80 the box. When this label is applied to the top of the box and the viewer looked directly down on the box, the effect created would be what is shown in Fig. 1, that is, instead of seeing the box in plan view, he would 85 think he was seeing it in perspective and that he was seeing its contents.

19 represents the top of a box having curved ends 20 and 21 provided with two substantially parallel sides 22 and 23. 24 90 shows a label carried by the top 19 of the box having a picture of a round box in perspective with a transparent top. This creates the same illusion as does the rectangular box.

25 represents the top of a box having intersecting sides 26 and 27, and 28 and 29. 95 30 and 31 indicate two sides of the box substantially parallel to each other and 32 indicates the label whereby a hexagonal appearing box is produced.

Thus it can be seen that any appearing shaped box can be produced by using the principles of this invention and therefore, I limit myself to no particular appearing 105 shaped box but to all shapes that can be produced hereunder. Neither do I limit myself to the articles which apparently are contained within the box or are shown in the picture on top of the box. Also the picture 110 need not necessarily be applied to the top of the box, but to any one of its sides, provided

the periphery or contour of the side is in accordance with the laws of perspective.

What I claim is:

1. In combination, a box having the contour of one of its faces fulfilling the laws of perspective, and a picture of a box in perspective carried by said face of the box whereby an illusion is produced.
2. In combination, a box having the contour of one of its faces provided with two of its sides substantially parallel and inclined away from the vertical, and a picture

of a box in perspective applied to said face of the box whereby an illusion is produced.

3. The device of claim 1 in which the picture is of a box having a transparent top.

In testimony whereof, I have signed my name to this specification this 2nd day of October, 1919.

D. ELLIS HAMBURGER.
